UNITED STATES PATENT OFFICE.

FREDERICK J. STUBING, SR., OF WHITE PLAINS, NEW YORK.

TREE-REPAIRING DEVICE.

Application filed April 24, 1925. Serial No. 25,555.

To all whom it may concern:

Be it known that I, FREDERICK J. STUBING, Sr., a citizen of the United States, and resident of White Plains, in the county of Westchester and State of New York, have invented certain new and useful Improvements in Tree-Repairing Devices, of which the following is a specification.

My present invention relates to the thorough and permanent repair of cavities in trees, and has particular though not exclusive reference to those of such size or shape as to require a subdivision in the filler, whereby it is divided into sections which may have a limited relative movement, by means of which the filler is able to sway with the tree in a wind and return uninjured to its normal position, thus avoiding cracks which would admit water and cause rot. So much is well known; but the attempt to solve the problem has generally been by interposing elastic water-proof material between the sections.

In my improvement I arrange iron plates, or plates of other metals, between the sections and secure them in place by bolts which are attached to each end of the plate and pass through the sound wood on each side of the cavity, approximately in a horizontal plane, the nuts on the ends being properly protected.

In the accompanying drawings, Figure 1 is a side elevation partly in section of a tree repaired by means of my improvement; Figure 2 is a projection of the plate I use; Figure 3 shows one of the bolts.

A is the tree, having a cavity of some extent, filled with cement concrete B. The plates C are shown dividing the filler into sections, as is common in this art. One of the plates is shown in Figure 2, and is preferably provided with holes c c, enabling the worker to attach bolts D in different lengths of plate. Bolts D such as are shown in Figure 3 engage the ends of the plates by means of pins D², and are inserted through the wood at the sides of the opening, being provided with washers D¹ and nuts D², which are embedded in the wood and protected by a cement filling E (see Figure 1) of any desired waterproof composition. The lowest plate in Figure 1 is shown in situ, with parts broken away for clarity. Ordinarily I employ $\frac{1}{4}$ " iron, making the plates of different sizes so as to select suit-

able lengths for different cavities. The ends of the bolts adjacent to the plates are formed into clevises for ready engagement.

The arrangement shown has many advantages over the criss-cross bolts passing diagonally through the concrete, which are sometimes used. The plates not only form a surface over which the concrete sections may slide to the small extent which experience has found to be sufficient, but form also supporting platforms on which the concrete may be put in place; besides which they may be made in the shop and kept in stock so that the work is expedited. In case of a serious defect appearing in a fine tree, only immediate repair can save it; and an intervening storm generally means destruction. When the cavity is relatively small, one bolt at each end may be sufficient, but in general it is better to support the plate by two at each end.

Having thus described my invention, what I claim is:

1. In the art of tree filling, a common means to support independently and hold in separated relation an individual section of a concrete filling for a tree cavity, including a plate extending transversely of the cavity below the section, and means for connection with the solid part of the tree to hold the plate in place.

2. In the art of tree filling, a common means to support independently and hold in separated relation an individual section of a concrete filling for a tree cavity, including a plate, extending transversely of the cavity below the section, and means for connection with the solid part of the tree to hold the plate in place, said means including two or more bolts pivoted to the ends of the plate and extending through the solid part of the tree at opposite sides of the cavity; and nuts engaging the bolts.

3. In the art of tree filling, a common means to support independently and hold in separated relation an individual section of a concrete filling for a tree cavity, including a plate, extending transversely of the cavity below the section, and means for connection with the solid part of the tree to hold the plate in place, said means including two or more bolts pivoted to the ends of the plate and extending through the solid part of the tree at opposite sides of the cavity; and nuts engaging the bolts, the plate having marginal

nal openings at intervals for the pivotal connection of the bolt at different points.

4. In the art of tree filling, a common means to support independently and hold in separated relation an individual section of a concrete filling for a tree cavity, including a plate, extending transversely of the cavity below the section, and means for connection with the solid part of the tree to hold the plate in place, said means including two or more bolts pivoted to the ends of the plate and extending through the solid part of the tree at opposite sides of the cavity; and nuts engaging the bolts the plate having marginal openings at intervals for the pivotal connection of the bolt at different points, the bolt slotted transversely to receive the edge of the plate and having a diametrical opening to register with one of the marginal openings.

5. In the art of tree filling, means to facilitate the insertion of a concrete filling in sections, and to support independently the sections, including plates arranged transversely of the cavity, and upon which the

sections of concrete may be built, and means to support the plates.

6. In the art of tree filling, means to facilitate the insertion of a concrete filling in sections, and to support independently the sections including plates arranged transversely of the cavity, and upon which the sections of concrete may be built, and means to support the plates, said means engaging the solid portions of the tree. 35

7. In the art of tree filling, means to facilitate the insertion of a concrete filling in sections, and to support independently the sections including plates arranged transversely of the cavity, and upon which the sections of concrete may be built, and means to support the plates, said means including bolts extending from the plate through a solid part of the tree, the plate having openings, and means for pivotally connecting the bolts with selected openings. 40

Signed at White Plains, N. Y. in the county of Westchester and State of New York this 20th day of April, A. D. 1925.

FREDERICK J. STUBING, Sr.
